A. BEHRSIN

OIL BURNER

Filed Nov. 5, 1923

Fig. 1.

UNITED STATES PATENT OFFICE.

AUGUST BEHRSIN, OF LOS ANGELES, CALIFORNIA.

OIL BURNER.

Application filed November 5, 1923. Serial No. 672,850.

To all whom it may concern:

Be it known that I, AUGUST BEHRSIN, a citizen of the United States, residing at Los Angeles, in the county of Los Angeles and State of California, have invented new and useful Improvements in Oil Burners, of which the following is a specification.

This invention relates to a liquid fuel burner, and more particularly pertains to a burner adapted for the combustion of oil with steam.

An object of my present invention is to provide an improved two-fluid burner, especially adapted for the burning of oil, and the utilization of steam in so doing.

Another object of my invention is to provide an oil burner which has an improved efficiency in the consumption of oil.

Another object of my invention is the provision of an oil burner which may be controlled with facility.

A still further object of my invention is to provide an oil burner which is capable of withstanding a heavy overload.

A still further object of my invention is the provision of an oil burner which will not be clogged by unburnt carbon.

Other objects may be inferred from a reading of the following specification:

30 In the drawings—

Fig. 1 is a plan view of my oil burner as applied to a furnace.

Fig. 2 is a longitudinal sectional view of the burner.

35 Fig. 3 is a perspective view of the body of the burner.

Fig. 4 is a perspective view of the drip plate.

40 Fig. 5 is a perspective view of a steam distributing plate.

Fig. 6 is a perspective view of a partition plate or diaphragm.

Fig. 7 is a perspective view of an oil-distributing plate.

45 Fig. 8 is a perspective view of a cap for the burner, and a hollow bolt.

Fig. 9 is an elevational view of an upper portion of the burner.

50 Fig. 10 is a cross section taken on line 10—10 of Figure 9.

More particularly, reference being had to Figure 3, 12 indicates the body portion of the burner which is here shown as comprising a cylinder 13 having an annular recess or groove 14 at its upper end, with a threaded inlet passage 15 extending from

the bottom of the cylinder for some distance into its interior, and opening into a chamber 16 of larger diameter than the passage 15. From the top of the chamber 16 to the bottom of the recess 14 of the cylinder extend four vertical cylindrical passages 17, 18, 19, and 20 which are ninety degrees apart, these passages emerging between the annular rim 21 of the recess and a mound 22 projecting from the bottom of the recess and terminating flush with the rim 21. A lug 23 attached to, or made integral with a part of the cylindrical surface of the cylinder 13, has a vertical channel 24 which is threaded at its lower end portion and extends nearly to the top of the lug. The lug 15 also has a horizontal channel or passageway 25 which is threaded at its outer end and communicates with the vertical channel 24. The horizontal channel 25 of the lug 15 is projected into the interior of the cylinder 13 out of communication with the channel 16 with a vertical passage or channel 26, threaded at its upper end, located centrally of the cylinder 13 and extending downwardly from the upper surface of the mound 22 into the interior of the cylinder until it communicates with the horizontal passageway 25.

In Figure 4 is shown a circular drip plate 30 of larger diameter than the cylinder 13 which is adapted to seat on the rim 21 and is formed with a central circular aperture 32 of substantially the same diameter as the vertical channel 26 of the cylinder 13 and is adapted to register therewith. The drip plate 30 has two oppositely disposed perforations 33 and 34 for the purpose of engaging fastenings as later described. Outwardly of the central aperture 32 are positioned four equal arcuate apertures 36, 37, 38 and 39 so disposed as to be located above the open upper ends of the passages 17, 18, 19 and 20, when the drip plate is assembled on the rim 21.

Figure 5 shows a steam distributing plate 40 having the general form of a star wheel gear, the diameter of which is substantially equal to the diameter of the cylinder 13. The steam distributing plate 40 has a central circular aperture 41 of substantially the same diameter as the central circular aperture 32 of the drip plate 30, and has eight radial slots 42 having curved diverging sides 43, the sides of one slot meeting the sides of its adjacent slot to form the tapered spurs 45 between adjacent slots. The extreme dis-

tance between the ends of the bottom wall of adjacent slots 42, as shown by line 46 in Figure 5, is substantially equal to the length of the median arc 47 shown in Figure 4 of the slots 36, 37, 38 and 39 of the drip plate 30. The steam distributing plate 40 has two oppositely disposed perforations 48 and 49, one in each of two spurs 45. The distance between the perforations 48 and 49 is equal to the distance between the perforations 33 and 34 of the drip plate 30, and are for the purpose of engaging fastening means, as later described.

In Figure 6 is shown a circular partition plate or diaphragm 50 of substantially the same diameter as the steam distributing plate 40. The diaphragm 50 has a central circular aperture 52 and has perforations 53 and 54, the same distance apart as the perforations 48 and 49 in the steam distributing plate 40, the perforations being for the purpose of engaging fastening means, as later described.

In Figure 7 is shown an oil distributing plate 56 which has a diameter equal to the diameter of the diaphragm 50. The oil-distributing plate 56 has a central circular aperture 57 of the same diameter as the central circular aperture 52 of the diaphragm, and has eight radial slots 58 extending from its periphery towards the center and having converging sides 59. Between the slots 58 of the oil-distributing plate are segments 60. The oil-distributing plate 56 also has two oppositely disposed perforations 61 and 62, the same distance apart as perforations 53 and 54 of the diaphragm 50, and are used for the purpose of engaging fastening means.

Figure 8 shows a cylindrical cap 64 having an aperture 65 passing axially therethrough which aperture leads to an annular recess 66 on the under side of the cap as shown in Figure 2. Outwardly of and concentrically with the recess 66 is a circular groove 67, the inner periphery of which is provided with radial apertures 68 which extend upwardly and interiorly to communicate with the recess 66.

In Figure 8 is also shown a bolt 72 having a head 73 and a threaded cylindrical stem 74. The stem 74 has a diameter equal to the central circular apertures in the plates 30, 40, 50, and 56, and equal to the diameter of the vertical aperture 65 in the cap 64. The stem 74 of the bolt 72 is hollow and has two opposite apertures 76 and 77 transverse of its axis. The stem 74 also has two other transverse opposite apertures 78 which are above the apertures 76 and 77.

In assembling the parts of the burner, the steam-distributing plate 40 is superimposed on the drip plate 30 so that spurs 45 of the steam-distributing plate bisect the apertures 36—37—38 and 39 of the drip plate and so

that the central circular aperture 41 of the steam distributing plate 40 is in alignment with the central circular aperture 32 of the drip plate. The perforations 48 and 49 of the steam-distributing plate 40 are also aligned with the perforations 33 and 34, respectively, of the drip plate 30. The diaphragm 50 is then superimposed on the steam-distributing plate 40 in such position that the perforations 53 and 54 of the diaphragm 50 are in alignment with the perforations 48 and 49, respectively, of the steam-distributing plate 40 and in such position that the central circular apertures 52 of the diaphragm will be in alignment with the central circular aperture 41 of the steam-distributing plate 40.

The oil-distributing plate 56 is then superimposed on the diaphragm 50 and aligned therewith. When the plates are in alignment it will be found that the oil-distributing plate 56 has its slots 58 overlying the slots 42 of the steam-distributing plate 40, the diaphragm 50 lying between the slots of the oil-distributing plate and of the steam-distributing plate. The plates 30, 40, 56 and the diaphragm 50 may then be secured to each other by screws which are passed through the apertures in each plate provided for the purpose. The combined plates and diaphragm thus form a unit which is superimposed on the cylindrical body 13 of the burner, the drip plate 30 being in contact with the upper rim 21 of the cylindrical body 13.

The cap 64 is then superimposed on the oil-distributing plate 56 and aligned therewith. The bolt 72 may then be passed through the vertical aperture 65 in the cap 64, through the central vertical apertures in the plates 56, 40, and 30 and the diaphragm 50 and screwed into the upper portion of the vertical channel 26 in the cylindrical body 13 until the head of the bolt is in contact with the upper surface of the cap.

In the functioning of the device, the steam is introduced into the channel 15 at the bottom of the cylindrical body 13. The steam then passes into the chamber 16 where it divides and passes through the four vertical passages 17, 18, 19 and 20. Emerging from these four passages the steam passes through the four slots 36, 37, 38 and 39 of the drip plate 30. The steam passing through any one of the slots 36, 37, 38 and 39 also passes vertically through two slots 42 in the steam-distributing plate 40 until it strikes the diaphragm 50, when it is deflected from the vertical into the horizontal position and issues from the slots between the drip plate 30 and the diaphragm 50. The oil is introduced through either one or both of the apertures 24 and 25 in the lug 23. In case the oil is introduced through only the vertical aperture 24 of the lug 23, the other

- aperture 25 may be stopped with a plug 80, shown in Figure 3. The oil passes through the horizontal channel 25 in the cylindrical body 13 at the end of which it enters the vertical central channel 26. In its passage upwardly through the vertical central channel 26 the oil enters the interior of the stem 74 of the bolt 72 and continues its passage through the stem 74 until it emerges through the transverse openings 76, 77, and 78 in the stem. After emerging from the transverse openings the oil passes into and through the radial apertures 68 in the cap 64. After emerging from the radial apertures 68 the oil passes through the slots 58 in the oil distributing plate 56 and is deflected in a horizontal direction by the diaphragm 50. On issuing from the slots 58 of the oil distributing plate 56 in a horizontal direction, the oil comes in contact with the steam issuing from the slots 42 of the steam distributing plate 40, whereupon the two fluids are properly combined for combustion.
- It will be seen that the burner thus constructed is adapted to discharge the steam and oil radially thereof throughout the periphery of the cylindrical burner body which renders the burner admirably suitable for use in a cylindrical fire box 81, as shown in Figure 1; the burner being located centrally of the fire box and connected to oil and steam feed pipes 82 and 83, respectively, leading from any suitable source of supply and filtered with regulating valves 84 and 85.
- If, however, it should be desired to direct the oil and steam from one side portion of the burner only, an annular sleeve 86 may be disposed to encircle the cap 64 as shown in Figures 9 and 10, which sleeve has a wall portion which extends over the discharge openings on the opposite sides of the diaphragm 50 and has a slot 87 through which a part of the discharge openings are exposed; the ends of the slot 87 having outwardly flared flanges 88 which serve as fuel spreaders in directing the fuel from the burner. The sleeve may be turned on the head 64 to direct the fuel from any desired side portion thereof.
- While I have described in detail a preferred form of my oil burner, modifications thereof may easily be made without departing from the essence of the invention; for example, the steam and oil distributing plates may, if desired, have each only one slot instead of a plurality, as shown. However, I desire it to be understood that such modifications come within the scope of my invention.
- I claim—
1. An oil burner, comprising a body member having a recess in its upper end and formed with a steam passage opening to said recess and also formed with a central oil passage, an apertured plate extending over the recess, a steam distributing plate above said apertured plate having radial open ended slots, a diaphragm extending over said steam distributing plate, an oil distributing plate above said diaphragm having open ended radial slots, a cap above said oil distributing plate having an oil chamber therein, and a tubular member leading from the central oil passage in the body member through said plates and diaphragm and having apertures opening to the oil chamber in said cap. 70
  2. In a two-fluid burner, in combination, a drip plate having a central aperture and other apertures, a steam distributing plate superimposed on said drip plate and having a central aperture and radial slots, a diaphragm superposed on said steam distributing plate and having a central aperture, and an oil distributing plate superposed on said diaphragm and having radial slots and a central aperture, said plates and diaphragm being axially aligned with each other, a body member, a cap, and connecting means extending through the central apertures of said plates and diaphragm and engaging said body member and cap. 80
  3. An oil burner, comprising a body member, a multi-branch steam channel, and an oil channel in said body member, a drip plate superimposed on said body member, said drip plate having apertures communicating with said steam channel, a steam distributing plate superimposed on said drip plate, said steam distributing plate having slots communicating with the apertures in said drip plate, and extending radially to the periphery of the steam distributing plate, a diaphragm superimposed on said distributing plate, an oil distributing plate superimposed on said diaphragm, said oil distributing plate having radially disposed slots extending to its periphery, said oil and steam distributing plates, drip plate and diaphragm having openings communicating with said oil channel in said body member, a cap superimposed on said oil distributing plate, an opening in said cap extending at least partly therethrough and axially aligned with and communicating with, the aperture in said oil distributing plate, apertures extending radially from said opening in said cap and communicating with said slots in said oil distributing plate, and means for fastening together the elements of said burner. 90
  4. An oil burner comprising a body member, a steam channel and an oil channel in said body member, a drip plate superimposed on said body member, said drip plate having apertures communicating with said steam channel, a steam distributing plate superimposed on said drip plate, said steam 100
  5. An oil burner comprising a body member, a steam channel and an oil channel in said body member, a drip plate superimposed on said body member, said drip plate having apertures communicating with said steam channel, a steam distributing plate superimposed on said drip plate, said steam 105
  6. An oil burner comprising a body member, a steam channel and an oil channel in said body member, a drip plate superimposed on said body member, said drip plate having apertures communicating with said steam channel, a steam distributing plate superimposed on said drip plate, said steam 110
  7. An oil burner comprising a body member, a steam channel and an oil channel in said body member, a drip plate superimposed on said body member, said drip plate having apertures communicating with said steam channel, a steam distributing plate superimposed on said drip plate, said steam 115
  8. An oil burner comprising a body member, a steam channel and an oil channel in said body member, a drip plate superimposed on said body member, said drip plate having apertures communicating with said steam channel, a steam distributing plate superimposed on said drip plate, said steam 120
  9. An oil burner comprising a body member, a steam channel and an oil channel in said body member, a drip plate superimposed on said body member, said drip plate having apertures communicating with said steam channel, a steam distributing plate superimposed on said drip plate, said steam 125
  10. An oil burner comprising a body member, a steam channel and an oil channel in said body member, a drip plate superimposed on said body member, said drip plate having apertures communicating with said steam channel, a steam distributing plate superimposed on said drip plate, said steam 130

distributing plate having slots communicating with the apertures in said drip plate, and extending radially to the periphery of the steam distributing plate, a diaphragm superimposed on said distributing plate, an oil distributing plate superimposed on said diaphragm, said oil distributing plate having radially disposed slots extending to its said drip plate, steam distributing plate, oil distributing plate and diaphragm having openings communicating with said oil channel in said body member, a cap superimposed on said oil distributing plate, said cap having an opening extending at least partly therethrough, axially aligned with, and communicating with, the aperture in said oil distributing plate, and having apertures extending radially from said opening in said cap and communicating with said slots in said oil-distributing plate, and means for fastening together the elements of said burner.

5. An oil burner, comprising a body member, a steam channel and an oil channel in said body member, a drip plate superimposed on said body member, said drip plate having apertures communicating with said steam channel, a steam distributing plate superimposed on said drip plate, said steam distributing plate having slots communicating with the apertures in said drip plate and extending radially to the periphery of the steam distributing plate, a diaphragm superimposed on said distributing plate, an oil distributing plate superimposed on said diaphragm, said oil distributing plate having radially disposed slots extending to its periphery, said drip plate, steam distributing plate, oil distributing plate and diaphragm having openings communicating with said oil channel in said body member, a cap superimposed on said oil distributing plate, an opening into said cap extending therethrough, axially aligned with and communicating with, the opening in said oil distributing plate, apertures extending radially from said opening in said cap and communicating with said slots in said oil distributing plate, and means for fastening together the elements of said burner, said means comprising a bolt the head of which engages said cap, and the stem of which passes through the opening in said cap, through the openings in said oil-distributing plate diaphragm, steam distributing plate and drip plate which communicate with said oil channel and into said oil channel to which it is secured, the stem of said bolt having an axial channel, and having at least one aperture extending from its channel to its periphery and communicating with said apertures which extend radially from said opening in said cap.

6. An oil burner, comprising a body member, a steam channel and an oil channel in

said body member, a drip plate superimposed on said body member, said drip plate having apertures communicating with said steam channel, a steam distributing plate superimposed on said drip plate, said steam distributing plate having slots communicating with the apertures in said drip plate, and extending radially to the periphery of the steam distributing plate, a diaphragm superimposed on said steam distributing plate, an oil distributing plate superimposed on said diaphragm, said oil distributing plate having radially disposed slots extending to its periphery, said slots of said oil distributing plate overlying said slots of said steam distributing plate, said drip, oil distributing and steam distributing plates and said diaphragm having openings in axial alignment communicating with said oil channel in said body member, a cap superimposed on said oil distributing plate, said cap having an opening extending therethrough, axially aligned with and communicating with, the opening in said oil distributing plate, apertures extending radially from said opening in said cap and communicating with said slots in said oil distributing plate, and means for fastening together the elements of said burner, said means comprising a bolt, the head of which engages said cap, and the stem of which passes through the opening in said cap, through the openings in said oil-distributing plate diaphragm, steam distributing plate and drip plate which communicate with said oil channel and into said oil channel to which it is secured, the stem of said bolt having an axial channel, and having at least one aperture extending from its channel to its periphery and communicating with said apertures which extend radially from said opening in said cap.

7. An oil burner comprising a body member, a steam channel and an oil channel in said body member, a drip plate superimposed on said body member, said drip plate having apertures communicating with said steam channel, a steam distributing plate superimposed on said drip plate, said steam distributing plate having slots communicating with the apertures in said drip plate, and extending radially to the periphery of the steam distributing plate, a diaphragm superimposed on said distributing plate, an oil distributing plate superimposed on said diaphragm, said oil distributing plate having radially disposed slots extending to its periphery, said slots of said oil distributing plate overlying said slots of said steam distributing plate, said drip, oil distributing and steam distributing plates and said diaphragm having apertures in axial alignment communicating with said oil channel in said body member, a cap superimposed on said oil distributing plate, an open-

ing into said cap extending therethrough axially aligned with and communicating with, the opening in said oil distributing plate, apertures extending radially from said 5 opening in said cap and communicating with said slots in said oil distributing plate, and means for fastening together the elements of said burner, said means comprising a bolt, the head of which engages said cap, and the 10 stem of which passes through the opening in said cap, through the openings in said oil and steam distributing plates, drip plate and diaphragm which communicate with said oil channel and into said oil channel to 15 which it is secured, the stem of said bolt having an axial channel, said stem having at least one aperture extending from its channel to its periphery, communicating with said apertures which extend radially 20 from said opening in said cap.

8. An oil burner comprising a body member, a steam channel and an oil channel in said body member, a drip plate superimposed on said body member, said drip plate 25 having apertures communicating with said steam channel, a steam distributing plate superimposed on said drip plate, said steam distributing plate having slots communicating with the apertures in said drip plate, 30 and extending radially to the periphery of the steam distributing plate, a diaphragm superimposed on said distributing plate, an oil distributing plate superimposed on said diaphragm, said oil distributing plate hav- ing radially disposed slots extending to its 35 periphery, the said slots of said oil distributing plate overlying said slots of said steam distributing plate in axial alignment therewith, said oil and steam distributing plates, drip plate and diaphragm having openings 40 in alignment and communicating with said oil channel in said body member, a cap superimposed in said oil distributing plate, an opening in said cap extending therethrough axially aligned with and communicating with, said opening in said oil distributing plate, apertures extending radially from said opening in said cap and communicating with said slots in said oil distributing plate, and means for fastening together the 45 elements of said burner, said means comprising a bolt, the head of which engages said cap, and the stem of which passes through the opening in said cap, through the openings in said steam and oil distributing plates, drip plate and diaphragm which communicate with said oil channel and into said oil channel to which it is secured, the stem of said bolt having an axial channel and having a plurality of apertures extending from its channel to its periphery, and communicating with said apertures which extend radially from said opening in said cap, and in axial alignment therewith, and means for fastening together said drip plate, 50 said steam distributing plate, said diaphragm, and said oil distributing plate. 55

AUGUST BEHRSIN.
